METALWORKING MACHINE

John J. McGlone, Harvey, and Robert I. Anderson, Chicago, Ill., assignors to Whiting Corporation, Harvey, Ill., a corporation of Illinois

Application November 21, 1942, Serial No. 466,514

9 Claims. (Cl. 164—60)

The present invention relates generally to machines for working metal in the form of sheets or plates. More particularly the invention relates to that type of metal working machine which serves selectively to carry out or effect offsetting, flanging, and slitting operations and embodies a C-shaped housing and supporting structure, a lower shaft disposed at the outer extremity or end of the bottom arm of the structure and extending upwardly and outwardly at approximately an angle of 45° with respect to the horizontal, a vertically movable head at the outer end of the top arm of the structure, an upper shaft on the head extending inwardly and downwardly at substantially a 45° angle and having its inner end disposed normally over and adjacent the outer end of the lower shaft, and power driven mechanism including gearing and drive shafts within the structure for conjointly driving the upper and lower shafts in opposite directions.

When it is desired to use a machine of this type for an offsetting operation, that is, to form offsets or jogs in metallic sheets or plates, a pair of complementary, coacting offsetting rolls are mounted on the upper and lower shafts, respectively, and an offsetting gauge attachment in the form of a roller equipped bracket for the purpose of gauging or determining the position of the offset or jog with respect to the edges of the work pieces is mounted on the bottom arm of the housing and supporting structure and adjusted to its desired gauging position relatively to the offsetting rolls. When it is desired to adapt the machine for carrying out a flanging operation on sheet or plate metal discs a pair of complementary, coacting flanging rolls are mounted on the upper and lower shafts, respectively, and a flanging hold-down attachment in the form of a pair of arms having rollers thereon for holding down and preventing upward bulging of the central portion of the work during drive and operation of the flanging rolls is mounted on the bottom arm of the housing and supporting structure and properly adjusted with respect to the rolls. When it is desired to use the machine for a slitting operation a pair of complementary coacting slitting rolls are mounted on the upper and lower shafts, respectively, and a slitting gauge attachment in the form of a rectilinear guide bar for gauging or determining the position or distance of the slit with respect to the edge of the work is mounted on the bottom arm of the housing and supporting structure of the machine and is adjusted to the desired gauging position relatively to the slitting rolls.

It has heretofore been proposed in connection with a metal working machine of the type under consideration to equip each of the various attachments with a separate or independent mount for attaching or applying it to the bottom arm of the housing and supporting structure. In practice it has been found that with a separate or independent mount for each attachment a great amount of time and labor is entailed in changing from one attachment to another in connection with different uses of the machine.

One object of the invention is to provide a metal working machine of the type and character under consideration which is an improvement upon, and may be more quickly and readily converted to different uses than, previously designed machines by reason of the fact that it embodies a common mount for the offsetting gauge attachment, the flanging hold-down attachment, and the slitting gauge attachment.

Another object of the invention is to provide a metal working machine of the last mentioned character in which the mount is so designed and constructed that it is capable of supporting not only the various attachments interchangeably but also two or more of the attachments while one is in readiness for use, that is, in its operative position.

A further object of the invention is to provide in connection with a metal working machine of the type under consideration a slitting gauge attachment of new and improved form.

A still further object of the invention is to provide a metal working machine as herein comprehended which is generally an improvement in the art and is characterized by compactness as well as facility of adjustment of the various attachments.

Other objects of the invention and the various advantages and characteristics of the present metal working machine will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a fragmentary side view of a metal working machine embodying the invention showing the offsetting gauge attachment, the flanging hold-down attachment, and the slitting gauge attachment all in place on the improved common

mount and with the offsetting gauge attachment in the position in which it is disposed when it is in use;

Figure 2 is a plan view of the machine, parts being broken away and other parts being shown in section for illustrative purposes.

Figure 3 is an enlarged horizontal section taken on the line 3—3 of Figure 1 and showing the offsetting gauge attachment in its operative position on the mount;

Figure 4 is an enlarged top or plan view showing in detail the construction and design of the offsetting gauge attachment;

Figure 5 is an enlarged side view of said offsetting gauge attachment;

Figure 6 is a vertical transverse section on the line 6—6 of Figure 5;

Figure 7 is an enlarged plan view showing the flanging hold-down attachment in its operative position;

Figure 8 is a transverse section taken on the line 8—8 of Figure 7 and illustrating in detail the construction and design of the last mentioned attachment;

Figure 9 is a side view of the flanging hold-down attachment;

Figure 10 is a reduced scale plan view of the slitting gauge attachment;

Figures 11 and 12 are respectively front and side views of the slitting gauge attachment; and

Figure 13 is a detail of the slitting rolls for the machine.

The machine which is illustrated in the drawings constitutes the preferred form or embodiment of the invention. It is adapted selectively to carry out or effect offsetting, flanging and slitting of pieces of sheet or plate metal and includes a pair of complementary coacting offsetting rolls 14 and 15, a pair of complementary coacting flanging rolls 16 and 17, a pair of complementary coacting slitting rolls 18 and 19, an offsetting gauge attachment 20, a flanging hold-down attachment 21, a slitting gauge attachment 22 and a common mount 23 for the attachments. The three pairs of rolls are adapted to be selectively used, depending upon the type of work that is to be done by the machine. The offsetting rolls 14 and 15 are adapted to be used with the offsetting gauge attachment 20 when it is desired to use the machine to form offsets or jogs in metallic work pieces. The flanging rolls 16 and 17 are adapted to be used together with the flanging hold-down attachment 21 when it is desired to use the machine to form downturned marginal flanges on circular or disc-like work pieces. The third set of rolls, that is, the pair of slitting rolls 18 and 19, is adapted to be used together with the slitting gauge attachment 22 when it is desired to employ the machine in connection with rectilinear slitting of metallic work pieces.

The machine, with the exception of the three attachments and the common mount 23 therefore, is of conventional or standard construction and comprises a C-shaped combined housing and supporting structure 24, a lower roll carrying shaft 25, a vertically movable head 26, an upper roll carrying shaft 27 on the head, and mechanism for conjointly driving the two roll carrying shafts. The housing and supporting structure comprises a hollow bottom arm 28, a hollow top arm 29 and a hollow connecting part 30 and is preferably in the form of a one-piece casting. The bottom arm 28 of the structure has a flat

top surface 31 and is so designed or constructed that the bottom portion thereof serves as a base for supporting the machine in an upright position on the floor or foundation of the establishment in which the machine is used. The top arm of the housing and supporting structure overlies, and is spaced a substantial distance from, the bottom arm 28 and is connected to the latter by way of the connecting part 30. The lower roll carrying shaft 25 is journalled in a bearing 32 at the outer extremity or end of the bottom arm 28 of the structure 24 and extends upwardly and outwardly at an angle of approximately 45° with respect to the horizontal. The 5 lower end of this shaft is housed within the bottom arm 28 of the structure 24 and the upper end is exposed and is adapted selectively to carry the rolls 15, 17 and 19. The head 26 carries the upper shaft 27 and overlies the upper or outer 10 end of the lower shaft 25. It is mounted for vertical sliding movement in a guideway 33 in the outer extremity or end of the top arm 29 of the structure 24 and is adapted to be raised or lowered by way of an upstanding screw shaft 15 20 25 30 35 40 45 50 55 60 65 70 75 34. This screw shaft, as shown in Figure 1, extends through a vertical internally threaded socket in a bracket 35 on the upper portion of the top arm 29 of the structure 24 and has a hand wheel 36 fixed to its upper end. The lower end 30 of the screw shaft is operatively connected to the upper portion of the head 26 so that the screw shaft is rotatable relatively to the head while at the same time the head is connected to the shaft so as to move vertically in connection with 35 such movement of the screw shaft. When the hand wheel 36 is rotated in one direction the head, together with the upper shaft 27, slides downwards towards the outer end of the bottom arm 28 of the structure 24 and when the hand wheel is reversely rotated the head and the upper shaft are caused to slide upwards in a rectilinear course. The upper shaft 27 is journalled in a bearing 37 on the lower portion of the vertically movable head 26 and extends 40 downwardly and inwards at substantially a 45° angle, as shown in Figure 1. The lower or inner end of the upper shaft is adapted selectively to carry the rolls 14, 16 and 18. The mechanism for conjointly driving the two shafts 25 and 27 45 comprises an electric motor 38 on the upper rear corner of the housing and supporting structure 24, a horizontally extending drive shaft 39 in the upper rear portion of the structure 24, a horizontally extending driven shaft 40 in parallel 50 relation with the drive shaft 39, change speed gearing 41 between the two last mentioned shafts, a horizontally extending driving shaft 42 in the top arm 29 of the structure 24, a horizontal driving shaft 43 in the bottom arm 28, clutch controlled gearing 44 for driving the drive shaft 42 55 from the driven shaft 40, a gear train 45 for driving the driving shaft 43 from the driving shaft 42, a pair of meshing bevel gears 46 and 47 between the front end of the driving shaft 42 and the upper outer end of the upper roll carrying shaft 27 for driving the latter shaft from the former shaft and a pair of meshing bevel gears 48 and 49 between the front end of the driving shaft 43 and the inner end of the roll carrying shaft 25 for driving the latter shaft from said driving shaft 43. The electric motor 38 is drivably connected to the drive shaft 39 by way of a pinion 50 and a gear 51. The change speed 60 gearing 41 between the driving shaft 39 and the 65 70 75 75

driven shaft 40 is in the form of pairs of meshing gears on the two last mentioned shafts and is controlled by a key (not shown) which is slidably mounted in a horizontal keyway 52 in the driven shaft 40 and is adapted, in response to longitudinal adjustment thereof, to lock any one of the gears on the driven shaft 40 for drive by the gear on the driving shaft that is in mesh therewith. Adjustment of the key is effected by way of mechanism including a hand lever 53. The clutch controlled gearing 44 is in the form of a loose pinion 54 on the rear end of the driven shaft 40 and a fixed gear 55 on the rear end of the driving shaft 42. The clutch for controlling such gearing comprises a driving clutch member 56 which is slidably and drivably mounted on the rear extremity of the driven shaft 40 and a driven clutch member 57 which is in opposed relation with the clutch member 56 and is fixed to the pinion 54 of the gearing 44. The clutch member 56 is shifted into and out of engagement with the clutch member 57 by way of mechanism including a hand lever 58 on the front or outer end of the top arm 29 of the housing and supporting structure 24. When it is desired to use the machine the hand lever 53 is manipulated so as to bring into operative position the desired pair of gears of the change speed gearing 41. Thereafter the electric motor 38 is started and this results in drive of the driven shaft 40 from the drive shaft 39 through the medium of the change speed gearing 41. After the motor 38 has reached its normal speed the clutch member 56 is shifted into engagement with the clutch member 57 by manipulation of the hand lever 58. Upon engagement of the two clutch members the driving shafts 42 and 43 operate conjointly to drive the roll carrying shafts 27 and 25, respectively. The gearing is so designed that the roll carrying shaft 27 is driven in a clockwise direction when viewed from the front of the machine and the lower roll carrying shaft 25 is driven in a counterclockwise direction.

The mount 23 serves as a medium for supporting interchangeably the offsetting gauge attachment 20, the flanging hold-down attachment 21 and the slitting gauge attachment 22. It is adapted, as hereinafter described more in detail to support any two of the attachments or all three of the attachments while one is in its operative or working position, and comprises a pair of guide rods 59 and 60. These two rods are arranged in parallel relation and extend horizontally. They are disposed at opposite sides of the combined housing and supporting structure 24 and are in straddled relation with the bottom arm 28 of said structure. The guide rod 59 is located at the so-called feed side of the machine, that is, the side from which the work pieces are fed in connection with offsetting and slitting operations. The rear end of said guide rod 59 is mounted in a horizontal, open-ended socket 61 in a horizontally elongated member 62. The latter has a flat upper portion which underlies, and is connected to, the horizontal leg of an angle bracket 63. The vertical leg of such angle bracket fits against, and is connected to, the connecting part 30 of the housing and supporting structure 24. Set screws 64 are disposed in threaded holes in the outer side portion of the member 62 and serve releasably to hold the rear end of the guide rod 59 in the socket 61. The front end of the guide rod 59 fits within a horizontal, open-ended socket 65 in one end of a horizontally elongated bracket 66 and is releasably secured in place by means of a set screw 67 which extends through the outer side portion of said one end of the last mentioned bracket. The central portion 5 of the bracket 66 fits against, and is connected to, the outer or front end of the bottom arm 28 of the structure 24. The guide rod 59 has a flat 68 on the bottom hereof and is normally rigidly held in place by way of the set screws 64 and 67. When the set screws are loosened the guide rod 59 may be removed from the sockets 61 and 65 by sliding it forwards beyond the bracket 66. The socket 65 in the bracket 66 is axially aligned with the socket 61 in the member 62. The guide rod 60 is located at the so-called discharge side of the machine, that is, the side from which the work pieces are discharged during offsetting or slitting operations. It is disposed in the same horizontal plane as the guide rod 59 and has the rear end thereof mounted in a horizontal open-ended socket 69 in a horizontally elongated member 70. Such member has a flat upper portion which underlies, and is bolted to, the horizontal leg of an angle bracket 71. The vertical leg of the angle bracket 71 fits against, and is bolted to, the adjacent side of the connecting part 30 of the combined housing and supporting structure 24. Set screws 72 extend through threaded holes in the outer side portion of the member 70 and serve releasably to hold the rear end of the guide rod 60 in the socket 69. The front end of the guide rod is mounted in a horizontal open-ended socket 73 in the other end of the bracket 66 and is releasably secured in place by a set screw 74 which extends through a threaded hole in the outer side portion of the part of the bracket 66 that defines the socket 73. Said socket 73 is axially aligned with, and the same in diameter as, the socket 69. When the set screws 72 and 74 are released the guide rod 60 may be removed from the sockets 69 and 73 by sliding it forwards. Said guide rod 60 has a flat 75 on the bottom thereof. It is of such length that when it is in its normal position the front end or extremity thereof projects beyond the socket 73, as shown in Figure 3 and for a purpose to be explained hereafter.

The pair of offsetting rolls 14 and 15 and the offsetting gauge attachment 20 are employed or utilized when the machine is used to form offsets or jogs in sheet or plate metal work pieces. The roll 14 is adapted to be mounted on the inner lower end of the upper shaft 27 and the roll 15 is adapted to be mounted on the outer upper end of the lower shaft 25, as shown in Figure 5 of the drawings. The periphery of the roll 14 has a 45° angle taper in the direction of the inner lower end of the shaft 27. The roll 15 is of composite character and comprises an outer part 15a and an inner part 15b. The peripheries of these two parts have a 45° angle taper, as shown in Figure 5. The plane of the periphery of the inner part 15b is inset with respect to the plane of the periphery of the outer part 15a of the roll 15 with the result that there is a step 15c between the two parts. When the two offsetting rolls 14 and 15 are mounted on the shafts 27 and 25, respectively, the two shafts are properly adjusted, one relatively to the other. The roll 14 is disposed over the inner part 15b of the roll 15 directly inwards of the step 15c and the two rolls are so arranged that during drive thereof they coact to effect an offset or jog in any work piece that is fed between them from the feed side of the machine to the discharge side. The offsetting

gauge attachment 20 serves as a means for gauging or determining the position of the offset or jog with respect to the edges of the work pieces that are fed between the rolls 14 and 15. It is designed and adapted when in use to be mounted on and carried by the guide rod 59 of the mount 23 and comprises a two piece cast metal bracket 76 and a roller 77. The bracket consists of a vertically elongated upper piece 78 and a bottom piece 79. The lower end of the upper piece has a downwardly facing groove 80 of semi-circular cross section for receiving the top portion of the guide rod 59. The bottom piece 79 of the bracket 76 is bolted to the lower end of the upper piece 78 and has an upwardly facing groove 81 of semi-circular cross section for receiving the bottom portion of the guide rod 59. The two grooves 80 and 81 define a cylindrical socket which permits the offsetting gauge attachment 20 to be slid longitudinally of the guide rod 59. Two set screws 82 extend through threaded holes in the central portion of the bottom piece 79 of the bracket 76 and serve, when tightened, to lock the bracket against displacement relatively to the guide rod 59. The upper or inner ends of these two set screws are adapted to engage the flat 68 on the bottom portion of the guide rod 59, as shown in Figure 6. The upper end of the upper piece 78 of the bracket is in the form of a pair of right angle webs, one of which is on the inside of the bracket and extends lengthwise of the bottom arm 28 of the combined housing and supporting structure 24 and the other of which is joined to, and projects outwardly from, the front margin of the one web and extends at right angles to the guide rod 59. The inner web is provided with a pair of vertically spaced, inwardly extending, integral ears 83 and these have vertically aligned circular holes 84. The roller 77 of the attachment 20 has a cylindrical outer periphery and is disposed between the ears 83. It is confined against vertical displacement by the ears and is rotatably mounted on a vertically extending shaft 85. The ends of the shaft fit within the holes 84 in the ears 83 and are locked in place by way of set screws or any other suitable means. The roller 77 is free to rotate about the shaft 85 and serves as a stop or guide for the inner edges of the work pieces that are fed between the complementary coacting offsetting rolls 14 and 15 (see Figures 4 and 5). The position of the roller 77 with respect to the offsetting rolls gauges or determines the distance of the offsets or jogs from the inner edges of the work pieces. By adjusting the attachment 20 rearwards on the guide rod 59 the offsets or jogs are inset an appreciable distance from the inner edges of the work pieces whereas forward adjustment of the attachment 20 on the guide rod 59 results in the offsets or jogs being inset but a small distance from the inner edges of the work pieces. When it is desired to adjust the attachment 20 the set screws 82 are released and the roller equipped bracket is shifted or slid to the desired position. Thereafter the set screws 82 are tightened so as to lock or fix the attachment 20 in place. The bracket 76 is so designed that the roller 77 projects above and below the operative portions of the offsetting rolls 14 and 15. When the attachment is in its operative position the roller 77 is located on the feed side of the machine but in close proximity to the two offsetting rolls. In order to hold the attachment in an upright position and against tilting in the direction of the bottom arm 28 of the combined housing and supporting structure

24 a vertically extending cap screw 86 is provided. This screw extends through an inwardly extending lug 87 on the lowermost ear 83 and is adapted to engage and slide on the flat upper surface of the lower arm 28 of the structure 24. In connection with use of the offsetting rolls 14 and 15 and the offsetting gauge attachment 20 a horizontal hold-down roller 88 is generally employed. This roller, as shown in Figure 5, is located outwards of the two offsetting rolls and is carried by a bracket 89 which is removably secured to the vertically movable head 26. When it is desired to provide offsets or jogs in sheet or plate metal work pieces the attachment 20 is adjusted or manipulated to the desired position and the machine is then started by connecting the two offsetting rolls for drive by the electric motor 38. Thereafter the work pieces are successively fed past the roller 77 of the attachment 20 and between the two rolls 14 and 15. During passage of the pieces past the two rolls the latter, in conjunction with the hold-down roller 88, form the desired offsets or jogs therein. The offsetting gauge attachment 20 may be removed either by withdrawing the bolts for clamping together the upper and bottom pieces of the bracket 76 or by loosening the set screws 82 and then sliding the guide rod 59 forwards so as to permit the bracket to be slid rearwards out of engagement therewith. But a single attachment 20 need be employed for the reason that in connection with an offsetting operation the direction of rotation of the offsetting rolls is such that the work piece tends to swing in the direction of the roller 77. 35 The flanging rolls 16 and 17 and the flanging hold-down attachment 21 are employed or utilized when the machine is used marginally to flange work pieces in the form of sheet or plate metal discs. The flanging roll 16 is adapted to be mounted on the inner lower end of the upper shaft 27 and has in the periphery thereof an annular groove of V-shaped cross section. The wall portions that define the groove are disposed at right angles to one another, as shown in Figure 40 9 and one extends horizontally and the other vertically. The other coacting flanging roll, that is, the roll 17 is adapted to be mounted on the upper outer end of the lower shaft 25 and has a bead type periphery of V-shaped cross section. 45 The two wall portions of the roll 17 that form the bead are disposed at right angles to one another and are adapted to fit within the annular groove in the roll 16 in connection with a flanging operation, as shown in Figure 9. During a flanging operation the work piece is placed on the flanging roll 17 and then, in connection with drive of the machine, the roll 16 is fed slowly and progressively toward the roll 17 for flange forming purposes. In connection with the flanging operation the disc-like work piece rotates due to rotation of the rolls and thus the entire margin of the piece is formed into a down-turned right angle flange at the conclusion of the flanging operation. The attachment 21 serves as a 50 medium for preventing upward deflection or bulging of the central portion of the work piece during flanging of the margin of the piece. It is in the form of a unit and consists of a horizontally elongated saddle type bracket 90, a shaft 91, a pair of sleeves 92 on the shaft 91, a pair of arms 93 on the sleeves, and a plurality of rollers 94 on the arms. The bracket 90 extends transversely across the bottom arm 28 of the combined housing and supporting structure 24 and has at the ends thereof downwardly facing

grooves 95 of semi-circular cross section for slidably receiving the upper portions of the guide rods 59 and 60. Two cap members 96 underlie, and are bolted to, the ends of the bracket 90 and these have upwardly facing grooves 97 of semi-circular cross section for slidably receiving the bottom portions of the two guide rods 59 and 60. Upstanding set screws 96a in the central portions of the cap members 96 serve when tightened to hold the flanging hold-down attachment 21 against sliding movement with respect to the guide rods 59 and 60. As shown in Figure 8, the upper ends of these set screws are adapted to engage the flats on the bottom portions of the guide rods. The grooves 95 at the ends of the bracket 90 and the upwardly facing grooves 97 in the cap members 96 define cylindrical, open-ended sockets which are of slightly greater diameter than the guide rods and permit the bracket, in connection with use of the attachment 21, to be slid back and forth on the guide rods into any desired position. The shaft 91 is disposed above, and in parallel relation with, the saddle type bracket 90 and is supported for vertical adjustment by way of a pair of eye bolts 98. The latter comprise eyes and depending threaded shanks and are located at the ends of the bracket 90. The eyes of the eye bolts encircle the ends of the shaft 91 and form bearings whereby the shaft 91 is permitted to rock back and forth. The shanks of the eye bolts extend loosely through apertured lugs 99 on the ends of the saddle type bracket 90 and carry upper nuts 100 and lower nuts 101. The upper nuts rest on the upper surfaces of the lugs 99 and the lower nuts serve as lock nuts. By loosening the lower nuts 101 and conjointly turning the upper nuts 100 vertical adjustment of the shaft 91 may be effected. When the shaft is vertically adjusted to the desired extent tightening of the lower nuts 101 will lock it in place against vertical displacement. The sleeves 92 are mounted in spaced relation on the central portion of the shaft 91 and are held against rotation relatively to the shaft by way of keys 102 which are connected to, and project outwards from, the shaft and fit within keyways 103 in the sleeves. The key and keyway connections between the sleeves and the shaft permit the sleeves to be adjusted to and from one another while maintaining the sleeves against rotation relatively to the shaft. The rear portions of the sleeves 92 are provided with set screws 104 for locking the sleeves against longitudinal movement on the shaft and the front portions of the sleeves are provided with forwardly extending, substantially horizontal lugs 105. The arms 93 of the flanging hold-down attachment 21 normally extend horizontally. They project forwards from the sleeves 92 and have the rear ends thereof positioned on top of the lugs 105. Vertically extending bolts 106 extend through aligned holes in the lugs 105 and the rear ends of the arms 93 and form pivots whereby the arms may be swung to and from one another (see Figure 7). When the bolts 106 are tightened the arms are clamped in place. When such bolts are loosened the arms may be swung to or from one another, as previously pointed out. The outer ends of the arms 93 are in the form of spindles and serve rotatably to support the rollers 94. Preferably each arm 93 is provided with a series of rollers. Collars 107 are mounted on the extreme front ends of the arms 93 and serve to hold the rollers in place. When the attachment 21 is in its operative position, as shown in Fig-

ures 7 and 9, the roller carrying arms 93 are located at one side of, but slightly above, the flanging roll 17 on the shaft 25 and engage the work piece on such roll so that in connection with a flanging operation the central portion of the work piece cannot bulge upwards. In connection with a flanging operation the central portion of the work piece being flanged exerts upward pressure on the rollers tending to rock the shaft 91 in a clockwise direction as viewed in Figure 9. In order releasably to lock the shaft 91 against such rocking movement a latch 108 is provided. This latch comprises a sleeve 109 and an eye bolt 110. The sleeve is keyed or otherwise fixedly secured to the end of the shaft 91 that overlies the guide rod 59, and has a rearwardly extending lug 111. The eye bolt 110 is disposed beneath the lug 111 and is pivotally supported by a pin 112 so that it may be swung back and forth between an operative position wherein it extends upwards and is substantially in dead center relation with the sleeve 109 and an inoperative position wherein it extends rearwards and permits the shaft 91 to rock in a clockwise direction as viewed in Figure 9. The pin 112 extends through the eye of the eye bolt 110 and is carried by a pair of laterally spaced upstanding lugs 113 on the end of the saddle type bracket 90 that is beneath the sleeve 109. The outer or distal end of the shank of the eye bolt is provided with a lug engaging abutment type nut 114 and this is normally locked in place by a jam nut 115. A tension spring 116 serves to urge the eye bolt into its operative or latching position. One end of this spring is connected to a screw 117 on the eye of the eye bolt and the other end of the spring is anchored to a screw 118 on the bracket 90. In connection with a flanging operation the work piece is properly positioned on the lower flanging roll 17. Thereafter the shaft 91 is rocked in a counterclockwise direction as viewed in Figure 9 in order to bring the rollers 94 into contact with the central portion of the top surface of the work piece. As soon as the shaft is so rocked the eye bolt 110 is swung upwards into its operative position wherein the nut 114 underlies the lug 111. After latching of the shaft 91 in place the machine is started and the upper flanging roll 16 is fed downwards by proper turning of the hand wheel 36. During the flanging operation the rollers 94 prevent upward deflection or bulging of the central portion of the work piece, as heretofore pointed out. At the conclusion of a flanging operation the eye bolt 110 is swung rearwards into its inoperative position in order to release the shaft 91 so that it may be rocked in a clockwise direction as viewed in Figure 9 for roller releasing purposes. Adjustment of the nut 114 on the shank of the eye bolt 110 serves to vary the locked position of the shaft 91 and the roller carrying arms 93. In order to facilitate swinging of the roller equipped arms for a flanging operation the shaft 91 is provided with a radially extending hand lever 119. The flanging hold-down attachment 21 may be adjusted to function in connection with a work piece of any particular diameter or thickness by sliding the bracket 90 either backwards or forwards on the guide rods 59 and 60, raising or lowering the shaft 91, and shifting the sleeves 92 to or from one another on the shaft 91. When the attachment 21 is not in use it may be slid to the rear ends of the two guide rods 59 and 60, as shown in Figure 1. The flanging hold-down attachment may be removed

from the mount 23 by releasing the guide rods 59 and 60, then sliding such rods forwards and thereafter sliding the attachment off the free rear ends of the guide rods.

The slitting rolls 18 and 19 and the slitting gauge attachment 22 are employed when it is desired to use the machine to slit work pieces in the form of metallic sheets or plates. The slitting roll 18 is adapted to be mounted on the inner lower end of the shaft 27 and the other roll, that is, the slitting roll 19, is adapted to be mounted on the upper outer end of the shaft 25. As shown in Figure 13, the two rolls are provided with coacting slitting edges and these are adapted, when the rolls are adjusted into slitting position, to overlap and effect slitting of any work piece which is fed between the two rolls. The attachment 22 serves as a medium for gauging or determining the distance of the slits from the inner edges of the work pieces. It is in the form of a unit and comprises a horizontally elongated guide bracket 120, a guide 121, a face plate 122, and a work piece support 123. The guide bracket 120 extends transversely of the bottom arm 28 of the combined housing and supporting structure 24 and has enlarged depending socket members 124 at its ends. Such members have cylindrical, open-ended sockets therethrough for slidably receiving the guide rods 59 and 60 constituting the common mount 23 for the various attachments. Set screws 125 extend through the lower portions of the socket members 124 and serve to lock the slitting gauge attachment 22 in its various adjusted positions on the two guide rods. The guide 121 is horizontally elongated and overlies and rests on the bracket 120. It is preferably in the form of a one-piece casting and has at the front thereof an upstanding flange 126 with a cutout 127 in its central portion. As shown in Figure 10, the guide 121 is slightly longer than the bracket 120 and extends transversely of the two guide rods 59 and 60. The front face of the upstanding flange 126 of the guide is flat and extends vertically. The face plate 122 fits against the front face of the guide flange 126 and is connected in place by screws or any other suitable means. It is the same in length as the guide 121 and has a central cutout 128 in registry with the cutout 127 in the flange 126. In connection with a slitting operation the inner or rear edge of the work piece slides along, and is guided by, the face plate 122. The work piece support 123 is approximately one-half as long as the face plate 122 and is connected to the end of the face plate 122 that is at the feed side of the machine. It is in the form of an angle bar and comprises a forwardly extending horizontal work supporting leg and a depending vertical leg. The vertical leg fits against and is screwed or otherwise fixedly secured to the lower portion of the adjacent end of the face plate 122. In connection with a slitting operation the work piece to be slit is placed in abutment with the feed end of the face plate 122 and is then slid in the direction of the rolls 18 and 19. During feed of the work piece past the rolls the horizontal leg of the work piece support 123 supports the rear margin of the work piece against downward movement. In practice it has been found that if the slitting gauge attachment is to guide the work pieces properly to the end that the slitting rolls form slits in true parallel relation with the inner edges of the pieces the face plate 122 must be maintained

at a slight angle to the cutting edges of the rolls as contradistinguished from truly normal. In order to permit the face plate to be positioned at the proper acute angle for perfect slitting the guide 121 has one end thereof pivotally connected to the subjacent end of the guide bracket 120 by way of a vertically extending pivot pin 129. This pivot pin permits the guide to be swung back and forth in a horizontal plane and hence makes it possible properly to adjust the angle of the face plate 122. A screw 130 extends through an arcuate slot 131 in the other end of the guide 121 and serves to lock the guide together with the face plate 122 in place. The arc of the slot 131 is concentric so far as the pivot pin 129 is concerned. The screw 130 extends into a threaded socket in the subjacent end of the guide bracket 120. When it is desired angularly to adjust the face plate 122 the screw 130 is released and the guide is swung until the face plate 122 is adjusted into its proper angular position with respect to the rolls 18 and 19. After proper adjustment of the face plate 122 the screw 130 is tightened so as rigidly or fixedly to secure the guide 121 to the bracket 120. In addition to the parts heretofore described the slitting gauge attachment comprises a roller 132. This roller is adapted to coact with a roller 133 to prevent twisting of the portion of the work piece 30 that is rearwards of the roll produced slit. During a slitting operation the slit portion of the work piece tends to twist in a counterclockwise direction as viewed in Figure 12. The rollers 132 and 133 coact to prevent such twisting. The roller 132 is carried by an arm 134 and the roller 133 is carried by an arm 135. The arm 134 is located behind, and extends in parallel relation with, the upstanding flange 126 of the guide 121. The outer end of said arm 134 overlies the guide 40 rod 60 and is pivotally mounted on a horizontally extending pivot pin 136. The latter is fixed to, and projects rearwardly from, the flange 126, and permits the arm 134 to swing in a vertical plane for adjustment purposes. The inner end of the arm 134 is provided with a horizontal, forwardly extending shaft 137 and this projects through the cutouts in the flange 126 and the face plate 122 and carries at its outer end the roller 132. A cap screw 138 extends through a lug 139 on the distal end of the arm 134 and fits within a threaded hole in the guide 121. This screw constitutes an adjustment whereby the arm may be swung upwards and downwards in order properly to position the roller 132. If thick work pieces are to be slit the arm 134 is swung upwards by proper turning of the screw 138 and if thin work pieces are to be slit the arm 134 is swung downwards by reverse turning of the screw. When the screw is properly adjusted or set it holds the arm 134 against swinging movement and hence locks the roller 132 in place. The roller 132, as shown in Figure 12, is adapted to overlie the rear margin of the work piece being slit. The roller equipped arm 135 is in the nature of a circular complementary attachment for use in connection with the main slitting gauge attachment 22, and has at one end thereof a socket 140 for receiving the front extremity of the guide rod 60, that is, the end portion of the guide rod that projects forwards of the bracket 66. The other end of the arm 135 embodies a horizontal, rearwardly extending pivot pin 141 for rotatably supporting the roller 133. It 55 also embodies a rearwardly extending lug 142

and this overlies the central portion of the bracket 66 and carries a depending abutment screw 143. The head of such screw rests on the central portion of the bracket 66 as shown in Figure 11 and the outer or free end of the shank of the screw fits within a threaded hole in the lug 142 and carries a lug or jam nut 144. By adjusting the screw 143 the roller 133 may be raised or lowered into its proper work piece engaging position. The roller 133 is adapted to underlie the front margin of the slit portion of the work piece. A collar 145 is removably connected to the front extremity of the guide rod 60 and serves to prevent forward displacement of the arm 135 when the latter is in its operative position. When the machine is not to be used for a slitting operation the roller equipped arm 135 is removed. Removal of the arm is effected by removing the collar 145 and then sliding the arm 135 off the front end or extremity of the guide rod 60.

When the machine is not in use the three attachments 20, 21 and 22 may be arranged on the mount 23 as shown in Figure 1 or they may be arranged in any other desired manner. In Figure 1 the slitting gauge attachment 22 is shown on the rear ends of the guide rods 59 and 60, the flanging hold-down attachment 21 is shown on the central portions of the two guide rods and the offsetting gauge attachment 20 is shown on the front end of the guide rod 59. With the attachments so arranged the offsetting gauge attachment may be used without disturbing the two other attachments. Should it be desired to use the flanging hold-down attachment 21 the offsetting gauge attachment 20 is removed and the attachment 21 is slid forwards and properly adjusted to render it operative. In the event that it is desired to use the machine for work piece slitting purposes the offsetting gauge attachment and the flanging hold-down attachment are removed and the attachment 22 is slid forwards and then properly adjusted. In connection with use of the machine for slitting purposes the supplemental slitting attachment in the form of the roller equipped arm 135 is mounted on the front end or extremity of the guide rod 60. By reason of the fact that the machine includes the mount 23, the three attachments 20, 21 and 22 may be employed interchangeably and it is possible quickly and readily to position any one of the attachments for use.

The herein described metal working machine is essentially compact and by reason of the fact that it includes the common mount 23 is characterized by facility of mounting or adjustment of the various attachments.

The invention is not to be understood as restricted to the details set forth since these may be modified within the scope of the appended claims without departing from the spirit and scope of the invention.

Having thus described the invention what we claim as new and desire to secure by Letters Patent is:

1. A metal working machine comprising a C-shaped combined housing and supporting structure, a pair of shafts mounted one at the outer end of the bottom arm of the structure and the other for vertical adjustment at the outer end of the top arm of said structure, and adapted selectively to support different pairs of complementary coacting rolls for use, respectively, with coacting attachments, power means including gearing in the structure for conjointly driving the shafts in

opposite directions; and a mount arranged and designed interchangeably as well as collectively to support said attachments for horizontal adjustment to and from the shafts, and embodying a pair of horizontal guide rods extending longitudinally along, and disposed slightly outwards of, one of the arms of the structure, a pair of brackets connected to, and extending outwards in opposite directions from, the outer end of the one arm and serving to support the adjacent ends of the rods, and a pair of brackets adjacent the inner end of the one arm and serving to support the other ends of the rods.

2. A metal working machine comprising a C-shaped combined housing and supporting structure, a pair of shafts mounted one at the outer end of the bottom arm of the structure and the other at the outer end of the top arm of said structure, and adapted selectively to support a pair of complementary coacting offsetting rolls, a pair of complementary coacting flanging rolls, and a pair of complementary coacting slitting rolls for use, respectively, with an offsetting gauge attachment, a flanging hold-down attachment, and a slitting gauge attachment, power means including gearing in the structure for conjointly driving the shafts in opposite directions, and a mount, adapted interchangeably as well as collectively to support said attachments for horizontal adjustment to and from the shafts and embodying a pair of laterally spaced horizontal guide rods at opposite sides of the bottom arm of the structure, a pair of brackets connected to, and extending outwards in opposite directions from, the outer end of said bottom arm and serving to support the adjacent ends of the rods, and a pair of brackets adjacent the inner end of said bottom arm and serving to support the other ends of the rods.

3. A metal working machine comprising a C-shaped combined housing and supporting structure having socket equipped brackets mounted thereon, a pair of shafts mounted one at the outer end of the bottom arm of the structure and the other for vertical adjustment at the outer end of the top arm of said structure, and adapted selectively to support different pairs of complementary coacting rolls for use, respectively, with coacting attachments, power driven mechanism including gearing in the structure for conjointly driving the two shafts in opposite directions, and a mount designed and adapted interchangeably and adjustably to support said attachments and embodying a pair of horizontal guide rods positioned normally at opposite sides of, and in parallel relation with, said bottom arm of the structure and carried by said socket equipped brackets so that they are slidable longitudinally.

4. In a metal working machine of the character described, the combination with a C-shaped supporting structure, a pair of shafts mounted one at the outer end of the bottom arm of the structure and the other for vertical adjustment at the outer end of the top arm of said structure and adapted to support a pair of complementary coacting slitting rolls, and power driven mechanism for conjointly driving the shafts in opposite directions, of a pair of horizontal guide rods mounted on the structure and positioned along and outwards of opposite sides of said bottom arm, and a slitting gauge attachment comprising a horizontally elongated bracket overlying and extending transversely across said bottom arm and having the ends thereof slidably mounted on the rods so that it is shiftable to and from the shafts, and a guide mounted on the bracket for

angular adjustment in a horizontal plane and provided with guide means for supporting and rectilinearly guiding work pieces during feed thereof between the rolls in connection with slitting thereof.

5. In a metal working machine of the character described, the combination with a C-shaped supporting structure, a pair of shafts mounted one at the outer end of the bottom arm of the structure and the other for vertical adjustment at the outer end of the top arm of said structure and adapted to support a pair of complementary coacting slitting rolls, and power driven mechanism for conjointly driving the shafts in opposite directions, of a pair of horizontal guide rods mounted on the structure and positioned along and outwards of opposite sides of said bottom arm, and a slitting gauge attachment comprising a horizontally elongated bracket overlying and extending transversely across said bottom arm and having the ends thereof slidably mounted on the rods so that it is shiftable to and from the shafts, a horizontally elongated guide overlying the bracket and pivotally connected thereto so that it is capable of being swung in a horizontal plane and provided with means for supporting and rectilinearly guiding work pieces during feed thereof between the rolls in connection with slitting thereof, and a bolt and arcuate slot connection between the guide and the bracket for releasably locking the latter together.

6. A metal working machine of the character described, comprising a C-shaped supporting structure, a pair of shafts mounted one at the outer end of the bottom arm of the structure and the other at the outer end of the top arm of said structure and adapted to support a pair of complementary coacting slitting rolls, power driven mechanism for conjointly driving the shafts in opposite directions, and a slitting gauge attachment embodying a horizontally elongated bracket overlying and extending transversely across said bottom arm and mounted so that it is shiftable to and from the shafts, and a horizontally elongated guide extending over and lengthwise of the bracket, provided with guide means for supporting and rectilinearly guiding work pieces during feed thereof between the rolls in connection with slitting, and connected to the bracket so that it may be adjusted angularly in a horizontal plane in order to position the guide means so that it operates in connection with slitting so to guide the work pieces that the slits are truly parallel to the edges in contact with said guide means.

7. A metal working machine of the character described, comprising a C-shaped supporting structure, a pair of shafts mounted one at the outer end of the bottom arm of the structure and the other at the outer end of the top arm of said structure and adapted to support a pair of complementary coacting slitting rolls, power driven mechanism for conjointly driving the shafts in opposite directions, and a slitting gauge attachment embodying a horizontally elongated bracket overlying and extending transversely across said bottom arm and mounted so that it is shiftable to and from the shafts, a horizontally elongated guide extending over and lengthwise of the bracket, provided with guide means for support-

ing and rectilinearly guiding work pieces during feed thereof between the rolls in connection with slitting, having one end thereof pivotally connected to the bracket so that it may be adjusted angularly in a horizontal plane in order to position the guide means so that it operates in connection with slitting so to guide the work pieces that the slits are truly parallel to the edges in contact with said guide means, and a bolt and arcuate slot connection between the guide and the bracket for releasably locking the bracket in the position into which it is adjusted.

8. In a metal working machine of the character described, the combination with a C-shaped supporting structure, a pair of shafts mounted one at the outer end of the bottom arm of the structure and the other for vertical adjustment at the outer end of the top arm of said structure and adapted to support a pair of complementary coacting slitting rolls, and power driven mechanism for conjointly driving the shafts in opposite directions, of a pair of horizontal guide rods mounted on the structure and positioned along and outwards of opposite sides of said bottom arm, and a slitting gauge attachment comprising a horizontally elongated bracket overlying and extending transversely across said bottom arm and having the ends thereof slidably mounted on the rods so that it is shiftable to and from the shafts, a guide mounted on the bracket for angular adjustment in a horizontal plane and provided with guide means for supporting and rectilinearly guiding work pieces during feed thereof between the rolls in connection with slitting thereof, and a roller disposed adjacent said guide means, mounted on the guide so that it is rotatable about a horizontal axis and is also vertically adjustable, and adapted to engage the top surfaces of the work pieces during slitting thereof.

9. A metal working machine of the character described, comprising a C-shaped supporting structure, a pair of shafts mounted one at the outer end of the bottom arm of the structure and the other at the outer end of the top arm of said structure and adapted to support a pair of complementary coacting slitting rolls, power driven mechanism for conjointly driving the shafts in opposite directions, and a slitting gauge attachment embodying a horizontally elongated bracket overlying and extending transversely across said bottom arm and mounted so that it is shiftable to and from the shafts, a horizontally elongated guide extending over and lengthwise of the bracket, provided with guide means for supporting and rectilinearly guiding work pieces during feed thereof between the rolls in connection with slitting, and connected to the bracket so that it may be adjusted angularly in a horizontal plane in order to position the guide means so that it operates in connection with slitting so to guide the work pieces that the slits are truly parallel to the edges in contact with said guide means, and a roller disposed adjacent said guide means, mounted on the guide so that it is rotatable about a horizontal axis and is also vertically adjustable, and adapted to engage the top surfaces of the work pieces during slitting thereof.

JOHN J. McGLONE.
ROBERT I. ANDERSON.
